NONBALLOONING SPINDLE FOR SPINNING MACHINES

Jan Weinberger, Brunn, Czechoslovakia

Application May 16, 1938, Serial No. 208,269

3 Claims. (Cl. 57—73)

This invention relates to certain new and useful improvements in Non-balloonning spindles for spinning machines.

The primary object of this invention is to provide a spindle for spinning machines in which the construction of the spindle is such that yarn or thread delivered from the drawing rollers of the spinning frame and directed through a guide is directly received upon the upper end of the spindle for loose and wide spiral winding thereon in a downward direction for delivery to the traveler which thereafter controls the winding of the yarn onto the tube and operates in the absence of all ballooning activities with substantially all stretching strains on the yarn eliminated and thereby reducing liability of breakage of the yarn.

A further object of the invention is to provide a spindle of the foregoing character wherein the guide through which the yarn passes from the front rollers of the drawing part of the spinning frame is in close relationship and directly above the spindle which results in an essential reduction of stretching of the yarn between said front rollers and the top of the spindle, with substantially all of the twist imparted to the yarn between said guide and the top of the spindle resulting in the production of a yarn that has a minimum of stretching action, while the amount of twist imparted thereto is variable from a point below the twist of a normal spinning machine up to an increased twist for the production of a more compact and hard yarn.

A still further object of the invention is to provide a spindle construction for spinning machines with devices associated with the spindle whereby ballooning activity of the yarn is eliminated which permits the utilization of larger rings forming guides for the travelers whereby a package of increased size and more compact winding is produced on a normal spinning machine.

More specifically, the invention relates to a particular improvement in the construction of the spindle head that is free of all surface or peripheral protuberances or projections so that a minimum of abutments or obstructions are presented to the yarn when leaving the guide and passing into contact with the head of the spindle, the gist of this invention residing in the provision of circumferentially spaced notches, grooves, depressions, or channels that extend longitudinally of the spindle with the deepest part thereof at the upper terminal end of the spindle with the side walls of the channels flaring outwardly to ward their lower ends while the bottom walls of

the channels graduate into lesser depth and finally merge into the cylindrical side wall of the spindle, defining adjacent their lower ends a convex bottom wall portion in each channel with the yarn received in a channel from the guide engaged by a side wall of the channel which wall prevents the imparting of further twisting action to the yarn, the latter riding out of a channel and into the succeeding channel during rotation of the spindle.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a side elevational view of a spinning machine spindle equipped with a novel construction of spindle head with parts of the spinning machine directly associated with the spindle being respectively diagrammatically illustrated and further illustrated in section.

Figure 2 is an enlarged fragmentary side elevational view of the spindle head, showing a longitudinally extending peripheral channel forming a twist-preventing guide for causing the yarn to be widely spirally wound on the tube in the absence of ballooning activity.

Figure 3 is a top end plan view of the head of the spindle showing the equidistant circumferentially spaced channels in the spindle head, the head being provided with at least one of such channels, three being illustrated, the channels being shown as of greatest depth at the upper terminal end of the spindle head, and

Figure 4 is a cross sectional view taken on line 4—4 of Figure 2, showing the bottom walls of the channels changing from concaved to convex forms in a direction toward the lower ends thereof.

It is known in the prior art to construct a spindle for spinning machines which eliminates ballooning activities of the yarn being wound thereon, but in such devices the yarn in being delivered from a guide to the head of the spindle moves into engagement with a multiplicity of projections or protuberances all of which have yarn engagement and the contact of said projections or protuberances with the yarn has a tendency to roughen surfaces of the yarn by frictional engagement of the projections or protuberances therewith and does not immediately arrest twisting action imparted to the yarn, such devices embodying projections or protuberances

only arresting such twisting action of the yarn at a point considerably spaced below the upper terminal end of the spindle and until the yarn begins its spiral winding movement on the spindle.

The present invention embodies a particular construction of spindle head and with which construction the yarn guide is closely associated, the construction of the spindle head being such that 10 twisting action imparted to the yarn is immediately stopped at the point of contact of the yarn with the spindle head, all twisting action that is imparted to the yarn being in the relatively small zone or space between the yarn guide and the 15 upper terminal end of the spindle, the yarn thereafter being widely spirally wound on the spindle for delivery to the traveler and ultimate winding in the usual manner onto the bobbin tube.

In the accompanying drawing which shows one 20 embodiment of the invention, the spindle 10 is rotatably mounted adjacent its lower end in bearings 11 and carries a pulley wheel 12 that is driven in the customary manner. The spindle 11 projects upwardly through a ring bar 13 diagrammatically illustrated and into which ring bar the 25 guide ring 14 is suitably set, the traveler 15 being associated with the ring bar. The yarn 16 delivered by the front rollers 17 of a part of the spinning frame is directed through a yarn guide 30 18 that is positioned above the upper end or head 19 of the spindle 10, the yarn guide 18 being in relatively close relationship to the upper terminal end of the spindle head 19 and disposed centrally thereof in line with the longitudinal axis of the 35 spindle and while the distance between the yarn guide and the upper terminal end of the spindle may be varied it has been found that best results can be obtained when the distance is approximately one-eighth of an inch.

40 The gist of the present invention resides in the particular designing and construction of the spindle head 19 which acts to stop twisting action imparted to the yarn 16 and to eliminate ballooning activity of the yarn by causing the latter to 45 widely spirally wind onto the spindle in a downward direction in its passage to the traveler 15 on the ring 14. The head 19 of the spindle is illustrated as provided with three equidistantly spaced peripheral longitudinally extending 50 notches, grooves or channels, but it is to be understood that such construction may embody a single channel, each channel designated in general by the reference character 20 comprising side walls 21 that are rounded at the points of 55 emergence with the peripheral surfaces of the spindle head 19 so as to offer a minimum of resistance of movement of the yarn into the succeeding channels 20 during rotation of the spindle. As shown in Figure 3, the greatest 60 depth of the channel is at the point 22 incident to the terminal end of the spindle head 19, while the bottom wall of the channel gradually rises into convex form in a direction toward the lower end of the channel as shown by the reference 65 character 23 in Figure 4 with said bottom wall finally merging into the peripheral wall of the spindle head 19. By arranging the channels 20 to extend longitudinally of the spindle head and with the side walls 21 of the channels flaring outwardly toward their lower ends, it is possible to 70 work the spindle in spinning machinery for clockwise and counter-clockwise rotation.

The yarn 16 as shown in Figure 1 in passing from the stationary guide 18 to the upper end of the spindle head 19 receives all twisting action

in the zone or space 24 between the guide 18 and the upper terminal end of the spindle head, the 5 yarn at the moment of its reception in a groove 20 for contact with the side wall 21 of the channel having all twisting action thereto arrested and in view of the smooth or polished surface of the walls of the channel and the rounding of the points of emergence of said side walls into the peripheral surface of the spindle head 19, there are no projections or protuberances present 10 which would tend to mar or roughen the surface of the yarn, the yarn passing successively into and out of the channels during rotation of the spindle for the production of a soft and smooth 15 yarn. The clinging of the yarn to the channeled head of the spindle causes the yarn to be widely spirally wound as shown at 16^a onto the head of the spindle 19 below the channels 20 and onto the tube 25 upon the spindle 10. The wide spiral winding 16^a leaves the tube as at 16^b for engagement with the traveler 15 and from the traveler the 20 yarn 16^c is wound upon the tube 25 as shown at 16^d to make the bobbin. The head channels 20 producing the wide spiral windings 16^a onto the spindle eliminate ballooning activities of the 25 yarn and thereby reduce breakage of the yarn during the winding of the bobbin, which breakage usually occurs in free swinging lengths or balloon areas of the yarn. Also, by producing the wide 30 spiral winding 16^a on the spindle and eliminating ballooning activities of the yarn, it is possible to employ a larger ring 14 for the production of a package of yarn of increased size on a normal spinning machine. With the construction of 35 spindle head, it is also possible to lengthen the tube 25 for a package of yarn of increased length and such a package of increased length and diameter permits longer operations of the spinning machinery with less frequent duffing for the 40 replenishing of tubes as well as reducing a wastage of yarn ends and improving the operation of the following process, such as weaving and winding. The head 19 of the spindle is illustrated as forming an integral part of a spindle body, but it is understood that such head may be constructed as a cap or attachment to a spindle of 45 normal construction.

From the above detailed description of the invention, it is believed that the construction and operation thereof will at once be apparent and 50 while there are herein shown and described the preferred embodiments of the invention, it is nevertheless to be understood that minor changes may be made therein without departing from the spirit and scope of the invention as claimed. 55

I claim:

1. A yarn spinning machine comprising a rotary spindle, a fixed yarn guide centrally disposed above the spindle in proximity thereto with the space between the guide and upper end of the 60 spindle constituting the sole zone in which a twist is imparted to the yarn, and the head of the spindle being constructed and arranged to eliminate ballooning of the yarn and to cause the 65 yarn to widely spirally wind on the spindle prior to the winding of the yarn on the spindle and to arrest twisting of the yarn at the point of contact of the yarn therewith and a traveler for directing the winding of the yarn on the spindle and said spindle head having a series of longitudinally extending circumferentially spaced channels having rounded side walls merging into the peripheral wall of spindle head with the yarn, during 70 rotation of the spindle, successively moving into the channel in the absence of obstructions 75

on the spindle head to eliminate damage or roughening of the yarn and to produce a soft and even yarn, said channels having the deepest portions at the upper terminal end of the spindle 5 head and the bottom walls of the channels gradually inclined outwardly towards their lower ends and preventing convex faces merging into the peripheral face of the spindle head.

2. A yarn spinning machine comprising a rotary spindle, a fixed yarn guide centrally disposed above the spindle in proximity thereto with the space between the guide and upper end of the spindle constituting the sole zone in which a twist is imparted to the yarn, and the head of 10 the spindle being constructed and arranged to eliminate ballooning of the yarn and to cause the yarn to widely spirally wind on the spindle prior to the winding of the yarn on the spindle and to arrest twisting of the yarn at the point of contact of the yarn therewith and a traveler for 15 directing the winding of the yarn on the spindle and said spindle head having a series of longitudinally extending circumferentially spaced channels having rounded side walls merging into the peripheral wall of the spindle head with the 20 yarn, during rotation of the spindle, successively moving into the channel in the absence of obstructions on the spindle head to eliminate damage or roughening of the yarn and to produce a 25 soft and even yarn, and the side walls of the channels flaring outwardly towards their lower ends at their points of mergence with the peripheral face of the head to offer the least resistance 30 to the movement of the yarn into and out of the successive channels.

3. A yarn spinning machine comprising a rotary spindle, a fixed yarn guide centrally disposed above the spindle in proximity thereto with the space between the guide and upper end of the spindle constituting the sole zone in which a twist 5 is imparted to the yarn, and the head of the spindle being constructed and arranged to eliminate ballooning of the yarn and to cause the yarn to widely spirally wind on the spindle prior to the winding of the yarn on the spindle and to 10 arrest twisting of the yarn at the point of contact of the yarn therewith and a traveler for directing the winding of the yarn on the spindle and said spindle head having a series of longitudinally extending circumferentially spaced 15 channels having rounded side walls merging into the peripheral wall of the spindle head with the yarn, during rotation of the spindle, successively moving into the channel in the absence of obstructions on the spindle head to eliminate damage or roughening of the yarn and to produce a 20 soft and even yarn, said channels having the deepest portions at the upper terminal end of the spindle head and the bottom walls of the channels 25 gradually inclined outwardly towards their lower ends and presenting convex faces merging into the peripheral face of the spindle head, and the side walls of the channels flaring outwardly 30 towards their lower ends at their points of mergence with the peripheral face of the head to offer the least resistance to the movement of the yarn into and out of the successive channels.
